UNITED STATES PATENT OFFICE.

CHARLES STELOW SCHWARTZ, OF KIRKSVILLE, MISSOURI.

END-GATE FASTENER.

1,240,608.

Specification of Letters Patent. Patented Sept. 18, 1917.

Application filed October 11, 1916. Serial No. 125,046.

To all whom it may concern:

Be it known that I, CHARLES STELOW SCHWARTZ, a citizen of the United States, residing at Kirksville, in the county of Adair,

5 State of Missouri, have invented certain new and useful Improvements in End-Gate Fasteners; and I do hereby declare the following to be a full, clear, and exact description of the invention, such as will enable others 10 skilled in the art to which it appertains to make and use the same.

This invention relates to improvements in wagon end gates, and particularly to fasteners therefor.

15 The principal object of the present invention is to provide a device for holding an end gate in closed position, said holding device being so constructed that it will not be jarred into released position by the jolting of the wagon.

Another object of the present invention is to provide a fastening device for an end gate that automatically tightens when moved into operative or holding position.

25 Other objects and advantages will be apparent from the following description when taken in connection with the accompanying drawing.

In the drawing:

30 Figure 1 is a rear elevation of an end gate equipped with my improved fastening device.

Fig. 2 is an elevation from the opposite side of the gate.

35 Fig. 3 is a vertical sectional view taken on the line 3—3 of Fig. 1.

Fig. 4 is a horizontal sectional view on the line 4—4 of Fig. 1, but showing the handle in released position.

40 Referring particularly to the accompanying drawing there is shown an end gate consisting of two sections 10 and 11, hinged together at 12. The ends of the sections of the gate are adapted to engage between the 45 cleats 13 carried by the sides of the wagon box 14. Secured to the section 10 and extending across the section 11, is an arm 15, the free end of which is formed with an open-ended slot 16. Secured to the outer

50 face of the free end of the said arm, and extending around the said slot, is a flat metal U-shaped plate 17. One end of this plate, preferably the lower arm thereof, is turned outwardly at right angles, as seen 55 at 18. Formed through the section 11, and in registry with the slot, when the said arm

is disposed across the section, is an opening 19, through which extends a bolt 20. On the outer end of the bolt is formed a radially extending weighted handle member 21, 60 the inner portion of which projects from the diametrically opposite side of the end of the bolt, thereby forming a transverse member 22, which is arranged to extend transversely of the slot 16, and bear on the outer face 65 of the U-shaped plate 17. The opposite, or threaded end of the bolt, projects through the other side of the section 11, and is engaged in a nut 23. Secured to the rear face of the said section, and formed with 70 an opening 24, through which the threaded end of the bolt passes, is an elongated strip of metal 25, the end at one side of the nut being bent outwardly at right angles, as shown at 26, for engagement with one side 75 face of the nut to prevent turning of the same, when the bolt is turned. It will be noted that the thread of the bolt is left-hand.

When the parts are in the position shown 80 in the sectional view, Fig. 4, it will be noted that the bolt is slightly withdrawn through the nut, but the handle member is resting on the lug or outturned portion of the U-shaped plate. In this position, the sections 85 of the end gate can be swung on their hinges and removed from the wagon. When again swung into proper position between the cleats, the handle is grasped and turned through the greater part of a circle until 90 stopped against the lower edge of the said lug. In thus turning the handle, the bolt is driven through the nut so that it will firmly clamp the section 11 of the gate and the free end of the arm 15 together. By 95 reason of the fact that the bolt tightens when turned into operative or locking position, it effectively prevents any movement toward release by the jarring or jolting of the wagon. The fact that the handle must 100 be turned through the greater part of a circle, further insures that the same will not be jarred into released position.

The tightening of the bolt also serves to more effectively clamp the parts of the gate 105 together, thus preventing any rattling thereof.

What is claimed is:

The combination with a sectional end gate having a slotted arm thereon, of a bolt 110 disposed through the gate and engageable in the slot, a nut engaged on one end of the

bolt, means for holding the nut against rotation, a U-shaped plate secured to the slotted end of the arm and partially inclosing said slot, one end of the said plate being provided with an outstanding stop lug, and a handle member carried transversely of the other end of the bolt and arranged to be disposed across the said slot,

the bolt moving through the nut when turned to operative position. 10

In testimony whereof, I affix my signature, in the presence of two witnesses.

CHARLES STELOW SCHWARTZ.

Witnesses:

JOHN W. NEFF,
J. C. WILLIAMS.
